UNITED STATES PATENT OFFICE.

VIRGINIA W. PIPER, OF JAMESTOWN, NEW YORK.

SYRINGE.

987,910.

Specification of Letters Patent. Patented Mar. 28, 1911.

Application filed April 20, 1910. Serial No. 556,472.

To all whom it may concern:

Be it known that I, VIRGINIA W. PIPER, a citizen of the United States, residing at Jamestown, in the county of Chautauqua 5 and State of New York, have invented new and useful Improvements in Syringes, of which the following is a specification.

This invention relates to syringe attachments which are particularly adaptable for 10 fountain syringes.

The object of the invention is to provide an attachment for the ordinary fountain syringes which may be placed upon the piping adjacent the syringe tube or nozzle in 15 such a manner as to receive the fluid expelled from the rectum or vagina and guide the same into a receptacle, and a still further object is the provision of means carried by the attachment for manipulating the device and which may be operated to cut off the 20 flow of fluid from the piping.

Further objects of the invention will appear as the following specific description is read in connection with the accompanying 25 drawing which forms a part of this application, and in which:

Figure 1 is a perspective view of the device with the handle shown in operative position for inserting the syringe tube. Fig. 2 is a 30 longitudinal sectional view. Fig. 3 is a transverse sectional view on the line 3—3 of Fig. 1. Fig. 4 is a perspective view showing in detail the alternative position of the handle when used to cut off the flow of fluid.

Referring more particularly to the drawing, 1 represents the ordinary syringe nozzle and 2, the rubber piping leading therefrom either to a compression bulb or to a rubber water bottle. The attachment which is applied to the syringe comprises a funnel-shaped member 3 having one of its sides 35 formed into a discharge spout 4 and its edges curved over into a retaining flange 5 which prevents the fluid used from coming out of the funnel except at the spout 4. Projecting rearwardly from the funnel-shaped member 3 is a piping tube 6 which is substantially semi-cylindrical in cross 45 section and which is provided with bearing

ears 7 projecting up from its side edges. 50 The ears 7 are apertured as at 8 to receive the pintles 9 which are carried by the end of the handle 10. The pivotal end of the handle has an eccentric extension 11 which when the handle is moved to the position shown 55 in Fig. 4, is brought into engagement with the flexible piping 2 and clamps the same into engagement with the inner side of the tube 6.

The operation of the device is as follows: 60 After the tank or bottle has been properly filled with water or other fluid and the handle shown in Fig. 4, the nozzle 1 is inserted in the vagina or rectum until the cup-shaped flange of the body 3 contacts with the person. The handle is now in the position shown in Fig. 1 and forms a ready support to hold the device in place at the same time permitting the water to flow through the piping 2 and the nozzle 1 to the affected parts. 65 The fluid which flows out of the vagina or rectum runs into the funnel-shaped body 3 and is discharged out the spout 4 into a receptacle placed in position for that purpose. 70

Heretofore in the use of vaginal syringes, 75 the fluid which was used after coming out of the vagina or rectum, was discharged promiscuously and frequently soiled the hands, the floor or any other thing with which it came in contact, especially were the fluid of 80 a caustic nature. When it is desired to stop the flow of fluid the handle is depressed to the position shown in Fig. 4 which will bring the cam extension 11 into engagement with the piping and pinch the same against 85 the inner side of the tube 6. This will stop the flow and permit the syringe to be withdrawn.

Having thus described the invention, what is claimed is—

1. In combination with the nozzle and flexible tubing of a syringe, of an attachment therefor comprising a funnel-shaped member, and a handle pivoted thereon for manipulating the syringe and cutting off 95 the supply of fluid to the tubing.

2. In combination with the nozzle and flexible tubing of a syringe, of an attach-

ment therefor comprising a funnel-shaped member, a handle pivoted upon the funnel-shaped member adapted for the manipulation of the syringe, and an eccentric extension on the handle adapted to compress the flexible tubing and cut off the fluid to the syringe.

In testimony whereof I affix my signature in presence of two witnesses.

VIRGINIA W. PIPER.
